[57] CLAIM

The ornamental design for a housing for optical scanner, as shown and described.

DESCRIPTION

FIG. 1 is a perspective view of a housing for optical scanner showing my new design;

FIG. 2 is a front elevational view thereof;

FIG. 3 is a rear elevational view thereof;

FIG. 4 is a top plan view thereof;

FIG. 5 is a side elevational view thereof, the opposite

side is a mirror image; and,

FIG. 6 is a bottom plan view thereof.
